United States Patent Office.

W. E. SMITH, OF HARTLETON, PENNSYLVANIA.

Design No. 2,773, dated August 27, 1867.

DESIGN FOR A FENCE.

The Schedule referred to in these Letters Patent and making part of the same.

TO ALL WHOM IT MAY CONCERN:

Be it known that I, W. E. SMITH, of Hartleton, in the county of Union, in the State of Pennsylvania, have originated and designed a new Pattern for Fence or other structure, of which the following is a full, clear, and exact description, reference being had to the accompanying drawing or photograph, making part of this specification.

Said design or pattern consists of a certain combination and arrangement of stalks, stems, buds, and flowers of a plant or plants, in cast metal or other material, as fully represented by the aforesaid print or drawing, which is sufficient, without further description or aid, to enable any one skilled in the art to model or construct the same for practical use.

What I claim as my invention, and desire to secure by Letters Patent, is—

The said design or pattern for fence or other structure, as here shown and described.
